UNITED STATES PATENT OFFICE.

FRANK M. CAWBY, OF CHAMPAIGN, ILLINOIS.

GARBAGE-RECEPTACLE.

1,239,881.

Specification of Letters Patent. Patented Sept. 11, 1917.

Application filed August 17, 1916. Serial No. 115,436.

To all whom it may concern:

Be it known that I, FRANK M. CAWBY, a citizen of the United States, residing at Champaign, in the county of Champaign, State of Illinois, have invented a new and useful Garbage-Receptacle; and I do hereby declare the following to be a full, clear, and exact description of the invention, such as will enable others skilled in the art to which it appertains to make and use the same.

This invention relates to a new and useful garbage receptacle, and an object of the invention is to provide a dominant or main garbage receptacle and an auxiliary receptacle, into which the garbage is first deposited, and is then dumped into the dominant receptacle.

The object in affording two receptacles, as aforesaid, is to retain the fumes or odor in the lower or dominant receptacle, particularly when emptying the garbage into the receptacle, thereby preventing the fumes or odor from backing up into the face of the one who is emptying the garbage.

Another object of the invention is to provide an odor or fume cut-off member between the two receptacles, which is normally closed when emptying the garbage into the auxiliary receptacle, and is then opened and closed by manipulating a rod, after closing the lid or cover of the auxiliary receptacle, thereby dumping the garbage from the auxiliary receptacle into the dominant receptacle.

In practical fields the details of construction may necessitate alterations falling within the scope of what is claimed.

The invention comprises further features and combination of parts, as hereinafter set forth, shown in the drawings, and claimed.

In the drawings:

Figure 1 is a view in side elevation of the improved garbage receptacle constructed in accordance with the invention.

Fig. 2 is a vertical sectional view through the same.

Fig. 3 is a plan view.

Fig. 4 is a sectional view on line 4—4 of Fig. 1.

Fig. 5 is a sectional view on line 5—5 of Fig. 1.

Fig. 6 is a sectional view on line 6—6 of Fig. 1.

Fig. 7 is a plan view of a stand or support for the dominant receptacle.

Fig. 8 is a detailed sectional view through a slide covered ventilating opening.

Referring more especially to the drawings, 1 designates a suitable base, to which, by means of screws 2, the legs 3 of a stand or support 4 are secured. This stand or support 4 consists of an annular ring 5, angular in cross section, and provided with the transverse bars 6, which, together with the flange 7, support the cylindrical dominant garbage receptacle 8. Telescopically fitted to the upper end of the receptacle 8 is a cylindrical hollow body member 9, the rib 10 of the receptacle 8 acting to support the body 9. The body 9 where it telescopically fits the receptacle 8 is provided with diametrically oppositely disposed slots 9^a and pins 8^a, for detachably connecting the body to the receptacle 8. To connect the body to the dominant receptacle, a partial turn may be imparted to the body, that is, after the body has been telescopically fitted to the receptacle, thereby causing the slots and pins of said connections to coöperate, to detachably connect the body to the receptacle. The body 9 is divided by means of a partition wall 11, disposed vertically, and a horizontal wall 12, to provide an idle compartment 13, and an open ended receptacle 14. Mounted in bearings 15 and 16 of the body 9 is a vertical rocking rod 17, having a handle 18 at its upper end, and a semi-circular disk 19 at its lower end, designed to close and act as a bottom to receptacle 14, that is when the rod 17 is rocked to close the disk 19. It is to be noted that the disk 19 and the collar 20 (which is secured to the rod by the pin 21,) prevent vertical movement of the rod 17. Moreover, it will be observed that the semi-circular edge of the disk 19 engages the groove 22 in the wall of the hollow body 9, thereby guiding the disk in its movement, when closing or opening the receptacle 14. Hinged at 23 to the top portion of the body 9 is a semi-circular lid or cover 24 the flange of which fits down over a semi-circular portion of the body 9 and closes the receptacle 14. The wall of the body 9 is provided with a plurality of apertures or perforations 25, constituting means to insure ventilation. Above the perforations or openings 25 is a larger opening 26, which may be covered or uncovered by means of a slide 27, which is mounted in the guides 28 upon opposite sides of the opening 26, there being an abut-

ment plate or shoulder 29 to limit the slide in its downward movement. Projecting inwardly from the wall of the body 9 is an auxiliary angular wall 30 forming a ventilating pocket 31, which is intended to hold some suitable disinfectant. This pocket 31 is adjacent the opening 26, there being perforations or apertures 32 in the bottom wall of the pocket, thereby allowing the fumes or odor to enter the pocket and pass through the disinfectant and exit or pass out through the opening 26, that is, when the slide 27 is opened. In using the garbage receptacle, the disk slide 19 is normally closed. Therefore, when depositing the garbage, the cover or lid 24 is thrown open, thereby permitting the garbage to be emptied into the receptacle 14. The cover or lid 24 is then closed, after which a rocking movement is imparted to the rod 17, thereby opening the disk or slide 19, dumping the garbage from the receptacle 14 into the dominant receptacle 8. Subsequently, the semi-circular disk 19 is closed, thereby retaining the fumes or odor in the receptacle 8, that is, when emptying garbage into receptacle 14.

The invention having been set forth, what is claimed as new and useful is:

- 20 1. In a garbage receptacle, the combination of a flanged support having alternate bars and elongated openings and a garbage can supported thereon and said can consisting of a dominant receptacle and an auxiliary hollow body telescoping the upper end of the dominant receptacle, of means for detachably connecting the body to said receptacle, said body having a vertical and horizontal wall dividing the same into an idle compartment and an open ended auxiliary receptacle, a cover for the upper open

end of the auxiliary receptacle, said body adjacent the bottom of the idle compartment and the lower open end of the auxiliary receptacle having an annular groove, a semi-circular partition slideable in said groove, in order to slide adjacent the under surface of the bottom of the idle compartment, to insure scraping the refuse from the upper face of the sliding partition, and a rocking rod mounted in bearings of the body and connected to the sliding partition for closing and opening the same, whereby the garbage may be dumped from the auxiliary receptacle into the dominant receptacle.

2. A garbage can, comprising a casing, the upper part of the can having a vertical wall dividing the upper part into a semi-circular idle compartment and a similar shaped garbage receptacle, said partition having an integral wall forming the bottom of the idle compartment, the outer wall of the can having an annular groove immediately adjacent the bottom of the idle compartment and the lower end of the auxiliary receptacle, a semi-circular closure mounted and slideable in said groove, whereby as the closure moves under the bottom of the idle compartment, the garbage may be scraped from the upper face of said closure, and a rod mounted in bearings of the can and connected to the closure for moving the same to dump the garbage from the auxiliary receptacle into the bottom of said can.

In testimony whereof I have signed my name to this specification in the presence of two subscribing witnesses.

FRANK M. CAWBY.
